UNITED STATES PATENT OFFICE

135,239

DESIGN FOR A GAME BOARD

William F. Drueke, Jr., Grand Rapids, Mich.

Application December 16, 1942, Serial No. 109,047

Term of patent 3½ years

To all whom it may concern:

Be it known that I, William F. Drueke, Jr., a citizen of the United States, residing at Grand Rapids, in the county of Kent and State of Michigan, have invented a new, original, and ornamental Design for a Game Board, of which the following is a specification, reference being had to the accompanying drawing, forming part thereof.

The figure is a plan view of a game board embodying my new design.

The game board is of conventional thickness and the design appears upon the top surface only.

I claim:

The ornamental design for a game board, as shown and described.

WILLIAM F. DRUEKE, JR.
